COMPRESSOR CONTROL SYSTEM

Frank O. Wallene, Lakewood, Ohio

Application March 26, 1932, Serial No. 601,393

4 Claims. (Cl. 230—21)

This invention relates to method and apparatus for automatically controlling, for any desirable reason, the amount of compression work done by a gas compressor, such as for economy in construction, design or operation of the compressor itself, or of the plant or system of which it forms a part, or for maintaining desirable conditions, such as a constant compressor discharge or suction pressure, or for any other reason.

10 One object of the invention is to provide improved method and apparatus of the character described, in which compressor control is secured by automatic adjustment or control of adjustable clearance pockets in step with or according to 15 variations in some suitable or desirable controlling factor.

More particularly, as applied to refrigeration, an object of the invention is to provide an improved gas compressor system sensitive to some 20 pressure value at the compressor, such as the suction pressure, and also to the flow of energy to the driver therefor, either for securing greater economy in operation or for avoiding peak loads in the energy supply, as will more fully appear.

25 Further objects and advantages of the invention will in part be obvious and in part will appear more clearly hereafter.

In the drawing, the view is a diagram, partly 30 in section, illustrating one embodiment of the invention.

According to modern practice, gas compressors are usually driven by constant speed drivers, either a constant speed electric motor or, in some cases, by a steam turbine operating most efficiently at a definite speed which desirably does not materially vary. With such drivers therefore, it is not possible or at least not conveniently possible, to vary the amount of compression work done by the compressor by changing the speed of the 40 driver, for which reason I resort to adjustment of a clearance pocket for the same purpose, and for purposes of illustration, assuming a compressor driven by a constant speed electric motor, I cause the adjustment of the clearance pocket to 45 be sensitive to both the amount of electrical energy required for compressor operation and to the pressure of the gas handled by the compressor.

The present invention, generally speaking, is 50 therefore based upon the well recognized ability to control the amount of compressor work done by a gas compressor, by providing it with adjustable clearance pockets by means of which it is possible to vary the effective volume of the cylinder chamber and consequently of the gas re-

maining in the chamber and its pocket at the end of the piston stroke, such remaining gas expanding 5 to assist the piston to return, and thereby reducing the work performed on each stroke. By automatically controlling or adjusting the volume of the clearance pocket or pockets, and by making the adjustment sensitive to a suitable or desirable factor of operation of the compressor or plant equipment supplied thereby, it is possible to produce or maintain certain desirable conditions. While the invention may be applied for use in a variety of ways, some of which will be described, it will be understood that it is not limited to these particular instances but is capable of some variation within the scope of the claims appended hereto.

Speaking first with reference to its application in the refrigerating art, it is possible to use the invention in at least two if not more ways. It may be taken advantage of to produce inherent economy of operation of the compressor itself, particularly when the required working load of the plant varies over a given period of operation, such as during the day. Again, where the power source comes from outside the plant, such as electrical current purchased from a power company, it may be desirable to avoid unduly high peak load because of the influence of peak load upon current cost. In such cases, the present invention is taken advantage of to avoid the use of an excess quantity of purchased power for the purpose of keeping the peak load within the desired maximum limit.

While the invention is capable of use on double acting or multi-stage compressors by providing 35 means for control of a part or all of the clearance pockets either simultaneously or in suitable harmony with each other, I have illustrated for convenience the application of the invention to a single acting compressor 1, the chamber 2 of 40 which communicates by way of an inlet valve 3 with the suction or supply pipe 4, and by way of an outlet valve 5 with the discharge pipe 6. The piston 1 is actuated by an electric motor 8 which may be assumed to be a constant speed 45 electric motor and which is supplied by current through the leads 9 from the main line source of current supply 10.

Chamber 2 communicates by way of an opening 11 with the adjustable clearance pocket 12, 50 which lies within a housing 13 attached to the compressor cylinder, one wall of the clearance pocket being formed by a piston 14 adjustable to and from any suitable manner, or by any suitable mechanism, operated hydraulically, elec- 55

- trically, or from any source of power, and shown as operated by providing it with a non-rotatable threaded stem 15 cooperating with a nut 16 in the hub of a gear 17 driven by an electric motor 18. 19 represents a vent pipe for relieving the pressure behind the piston 14 and returning the same to the suction or supply line, as is usual.
- The control system for the compressor described may include any suitable or desirable instruments for the purpose of securing control sensitive to the pressure of the gas at the compressor, either suction or discharge, as may be desirable or necessary, and also sensitive to the power input to the compressor driver. For illustration, and not in any sense of limitation, I have shown the control system as comprising two instruments, marked respectively A and B, the first of which is sensitive to the electrical energy input to the compressor driver 8 and the second of which is sensitive to the compressor pressure, the two instruments conjointly controlling operation of the clearance pocket adjusting motor 16.
- Electrical instrument A of course is of a character suitable to the kind of current required for motor 8. For an A. C. system, it will be similar to a polyphase or single phase meter. For a D. C. system it may be similar to a D. C. watt meter. In the arrangement shown, which supplies alternating current to motor 8, instrument A includes a disc 20 carrying an arm 21 and influenced by coils 22, 23 supplied by current transformers 24, 25 associated with leads from the supply line to motor 8, and also sensitive to potential coils 26, 27 suitably connected to the line. The torque developed by the disc 20 is proportional to the amount of power taken from the supply leads by motor 8 and is balanced against an adjustable loading spring 28.
- Instrument B includes a pipe 29 communicating with the compressor so as to be responsive to its pressure, and in the instance shown communicating with the suction side of the compressor. Said pipe also communicates with a bellows 30, the movable part of which actuates a rack 31 operating a pinion 32 with which rotates an oscillating arm 33, the bellows pressure being balanced against the usual adjustable loading spring 33a.
- Arm 21 of instrument A is connected by a link 34 to arm 35 pivoted at 36 and carrying a double ended contact member 37 cooperating with two adjustable contacts 38, 39 on the arms of a yoke carried by a lever 40 also pivoted at 36 and working between adjustable limit stops 41 and connected by link 42 to be operated by arm 33.
- The center contact is connected by a wire 37a to the center one of the supply leads, while the contacts 38, 39 are connected through coils 43, 44 to one of the other leads, for actuating the reversing switch marked generally 45. These two coils 43, 44, separately actuate the switch parts 45a, 45b, which connect the motor 18 to the main leads 10, so as to cause rotation of said motor in one direction or the other according to which switch part is closed, and to thereby either increase or decrease the volume of the clearance pocket or pockets, as may be required by the control operation in progress.
- Let it be assumed that 46 represents any refrigerating system or apparatus supplied with refrigerant by the compressor through its discharge line 6, the refrigerant returning to the compressor as a gas by way of the suction line 4.
- Gas enters the compressor cylinder through

valve 3 as the piston moves to the right. As it completes its stroke and returns, valve 3 closes and gas escapes through valve 5 to the discharge line 6 when the pressure in the cylinder rises slightly above that in the discharge line. A certain amount of gas has been trapped in clearance pocket 12 and such other clearance space as is necessary for mechanical reasons between the piston and cylinder head. As piston 7 starts to return, the gas in the clearance space, including pocket 12, expands to a pressure slightly below that in pipe 4, whereupon valve 3 again opens and fills the cylinder during the suction stroke to a pressure nearly equal to that in the suction line 4.

If piston 14 has been so adjusted that it lies in a position to close the opening 11 between the clearance pocket and the compressor cylinder, it is obvious that when piston 7 starts its suction stroke there will only be a small amount of clearance gas, and only a small movement of piston 7 is required to bring the clearance gas pressure down to a pressure below that in pipe 4, resulting in valve 3 opening much sooner than when the volume of clearance space is greater, or, in other words, when piston 14 has been adjusted to a position such as shown in the drawing. It is obvious therefore that the amount of work done by the piston 7 can be varied considerably by an adjustment of piston 14 to increase or decrease the clearance volume of the cylinder.

Let us assume that in a plant where this system is in operation the electrical supply lines 10, by way of conducting wires 47, supply plant equipment, conventionally illustrated at 48, other than the refrigerating system 46. Such other plant equipment, for example, may be machinery or other parts requiring electrical energy.

Assume also that the power demand by the refrigerating system constitutes an appreciable portion, say 50% to 75% of the total power demand of the plant as a whole, and that 100 kw. has been determined as the maximum power demand permissible, because if the peak load is permitted to go beyond that value the cost of electric current becomes excessive. It is therefore desirable to keep the total current consumption in the plant below 100 kw.

Let it be further assumed that the total plant load, for some reason such as an increase of energy demand by the equipment 48, tends to increase the load to 101 kw., the effect of this increase being to cause rotation of disc 20 and closing of contacts 37, 39. As a result coil 44 is energized, closing the switch 45b and causing motor 18 to rotate to increase the clearance space 12 by moving the piston 14 to the left. This instantly produces a decrease in the amount of power required by motor 8 and therefore in the current taken from the leads 10, reducing the torque applied to the disc 20, with the result of opening the contacts 37, 39, and motor 18 stops. The gas pressure in the pipe 4 is not likely to change very quickly. In fact, under usual plant conditions it may require an hour or more before there is a noticeable change, because the lag in the effect through the refrigerating apparatus is quite material. However, the controlling system has instantly reduced the power demand and keeps it within the required maximum.

Suppose that current demand recedes to 99 kw. and that tension of spring 28 is such that the disc 20 therefore rotates to the left, closing contacts 37, 38. Coil 43 is now energized, closing the switch 45a and causing motor 18 to rotate in the

opposite direction and thereby decreasing the clearance space, which in the same manner causes the motor 8 to take more power, resulting in an increase in the torque in disc 20, which again opens contacts 37, 38, so that the motor 8 stops.

The parts of the controlling mechanism, that is to say, of the instruments A, B, are so formed, such as by the spacing of the yoke arms of lever 40, and are so adjusted, such as by adjustment 10 of the stops 41, of the tension of the springs 28, 34, and of the location of the adjustable contacts 37, 38, 39, as to absolutely prevent the current input to the plant as a whole exceeding the desired maximum, 100 kw. in the instance under 15 consideration, and at the same time are so formed and adjusted as to insure that at least sufficient current is used to operate the compressor up to its maximum capacity within the limits of the maximum current peak. When an electrical demand, by the plant as a whole, tends to exceed the 20 desired maximum at a time when additional refrigeration is also required, it is obvious that such additional refrigeration will not be immediately provided but the effect of the demand therefor will be retained in the controlling system so that when the electrical demand of the plant as a whole later drops to a value within the maximum permissible amount, the duty of supplying the necessary extra refrigeration is immediately assumed and satisfied.

The invention, however, is not limited to use for the purpose of limiting the maximum electrical input to the plant as a whole, but may be applied for use in securing reasonably constant suction pressure and thus securing economy in the operation 35 of the compressor itself. In such an arrangement, for example, the instrument B may be subject to the intake pressure to the compressor and instrument A may be subject to the current supply leads to the compressor driver only, and the control parts are formed and adjusted as described, so that the current input is limited to that amount which will properly operate the compressor at the desired capacity. If at any time while so operating 40 there is a demand for additional refrigeration, the effect of such demand again will be retained in the control system so that the additional refrigeration can be supplied when the refrigerating load is later reduced. Such an arrangement is useful where the refrigerating load varies materially during the day, being heavier at night, for example, than in the day time or vice versa.

The invention may also be applied for use in the operation of compressors for other fluids, such as an air compressor, where it may be desirable to maintain a given discharge pressure but nevertheless prevent the power input to the compressor driver from exceeding a given maximum. Here instrument B is made subject to the compressor discharge pressure and instrument A to the current input to the driver for the compressor.

In all instances described, as well as others to which the invention may be applied, it has the advantages of providing a graduated, uniformly varying or modulated adjustment of the compressor load by graduated adjustment of the clearance pocket volume, the system functioning more or less as an automatic governor. The 65 clearance pocket adjuster, such as the motor 18

or its equivalent, works back and forth, first increasing and then diminishing the clearance pocket volume in accordance with conditions, but always with a tendency to come to rest at the desired position as soon as possible. As a consequence, the entire system tends to maintain the most efficient operating conditions, as well as securing the necessary limitation of power input within any desired maximum value to avoid excessive peak loads, as will be readily understood. 10 To accomplish this commercially, in some cases, such as in a refrigerating plant, it may be necessary to utilize a brine storage or heat accumulator, as it may be termed, for the purpose of absorbing heat during the peak loads when the 15 gas compression work is done at a reduced rate.

Other advantages and uses of the invention will readily be apparent to those skilled in the art.

What I claim is:

1. In combination, a compressor, a power operated driver therefor, said compressor having an adjustable clearance pocket, and means sensitive to variations in the intake pressure at the compressor and to variations in the power input to the 20 driver for gradually adjusting the clearance pocket.

2. In combination, a pressure utilizing system, a compressor arranged to supply pressure to said system, a power operated driver for said compressor, said compressor having an adjustable clearance pocket, and means sensitive to variations in the intake pressure at the compressor and to variations in the power input to the 30 driver therefor for gradually adjusting the clearance pocket.

3. In combination, a pressure utilizing system, a compressor in circulatory communication therewith and thereby arranged to supply pressure to said system, said system being of such 40 character that variation in the intake pressure of said compressor is materially delayed following variation in compressor output, a power operated driver for said compressor, means for adjusting the clearance space of said compressor, and means for controlling said last named means, said controlling means being sensitive to variations in the intake pressure of said compressor and being adapted to maintain a predetermined 45 power input to said driver.

4. In combination, a pressure utilizing system, a compressor in circulatory communication therewith and thereby arranged to supply pressure to said system, said system being of such inherent character that variation in the intake 55 pressure of said compressor cannot promptly follow variation in compressor output, a power operated driver for said compressor, means for adjusting the clearance space of said compressor, whereby increased clearance space corresponds to decreased output of said compressor and to decreased power input to said driver, and a controller for said adjusting means arranged to move in clearance-space-decreasing direction in response to an increase in the intake pressure of 60 said compressor, said controller having another connection for stopping its movement in response to decrease in said power input.

FRANK O. WALLACE. 70
